(57) **CLAIM**

The ornamental design for a flying ball, as shown and described.

DESCRIPTION

1. Flying ball
2. Flying ball
3. Flying ball
4. Flying ball
5. Flying ball
6. Flying ball

FIG. 1.1 is a photo of a front perspective view of a flying ball showing our design.

FIG. 1.2 is a photo of a rear perspective view of the flying ball in FIG. 1.1.

FIG. 1.3 is a photo of a front elevation view of the flying ball in FIG. 1.1.

FIG. 1.4 is a photo of a rear elevation view of the flying ball in FIG. 1.1.

FIG. 1.5 is a photo of a left side elevation view of the flying ball in FIG. 1.1.

FIG. 1.6 is a photo of a right side elevation view of the flying ball in FIG. 1.1.

FIG. 1.7 is a photo of a top plan view of the flying ball in FIG. 1.1.

FIG. 1.8 is a photo of a bottom plan view of the flying ball in FIG. 1.1.

FIG. 2.1 is a photo of a front perspective view of a flying ball showing our design.

FIG. 2.2 is a photo of a rear perspective view of the flying ball in FIG. 2.1.

FIG. 2.3 is a photo of a front elevation view of the flying ball in FIG. 2.1.

FIG. 2.4 is a photo of a rear elevation view of the flying ball in FIG. 2.1.

FIG. 2.5 is a photo of a left side elevation view of the flying ball in FIG. 2.1.

FIG. 2.6 is a photo of a right side elevation view of the flying ball in FIG. 2.1.

FIG. 2.7 is a photo of a top plan view of the flying ball in FIG. 2.1.

(Continued)

FIG. 2.8 is a photo of a bottom plan view of the flying ball in FIG. 2.1.

FIG. 3.1 is a photo of a front perspective view of a flying ball showing our design.

FIG. 3.2 is a photo of a rear perspective view of the flying ball in FIG. 3.1.

FIG. 3.3 is a photo of a front elevation view of the flying ball in FIG. 3.1.

FIG. 3.4 is a photo of a rear elevation view of the flying ball in FIG. 3.1.

FIG. 3.5 is a photo of a left side elevation view of the flying ball in FIG. 3.1.

FIG. 3.6 is a photo of a right side elevation view of the flying ball in FIG. 3.1.

FIG. 3.7 is a photo of a top plan view of the flying ball in FIG. 3.1.

FIG. 3.8 is a photo of a bottom plan view of the flying ball in FIG. 3.1.
